UNITED STATES PATENT OFFICE.

HARRY N. LATEY, OF NEW YORK, N. Y., ASSIGNOR TO AUTOMATIC TRAIN STOP COMPANY, A CORPORATION OF MAINE.

ELECTRIC TRAIN-CONTROL SYSTEM.

1,111,394.

Specification of Letters Patent. Patented Sept. 22, 1914.

Application filed March 5, 1909. Serial No. 481,388.

To all whom it may concern:

Be it known that I, HARRY N. LATEY, a citizen of the United States, residing at the city of New York, in the borough of Manhattan and State of New York, have invented certain new and useful Improvements in Electric Train-Control Systems, of which the following is a full, clear, and exact description.

10 This invention relates to train control systems, being a system or installation by which signals and other prescribed traffic conditions are automatically enforced.

In the pending applications Nos. 466,253, filed Dec. 7, 1908, and 478,869, filed Feb. 19, 1909, and in Patent No. 879,028, granted Dec. 31, 1907, of Ernst Woltmann, there are set forth installations having certain broad features or principles by which a sectional 20 third rail or trolley of an electric railroad is made use of as a line conductor for the power current transmission. The installations above referred to, have certain common dominant characteristics, which have been set forth with particularity in the patent and in the pending application No. 466,253, to which reference may be made for a more extended consideration of these general principles.

30 The invention of the present application relates primarily to securing the principal functions of the foregoing cases and some additional functions with normally closed operating circuits throughout, whereby all parts come to train stopping conditions in case of breakage of any circuit or conductor, or short circuiting, or failure of current in any source. The present invention also secures all its purposes entirely independent of any semaphore or signal systems, being self contained and entirely self operating, whether the usual signal system operates or fails utterly.

Figure 1 of the drawing shows, somewhat diagrammatically, a practical installation embodying the principles of my invention. Fig. 2 is a detail showing a power distribution point or station.

Referring to the drawing in which like parts are designated by the same reference sign, 1 designates a track-way. Each track-way has a usual third-rail or trolley 2 to which power is normally supplied at both ends. The third or power rails or trolleys

ordinarily employed are heavily made to stand the rough usage to which they are exposed in the engagement of the contact shoes of trains and in other ways, so that they necessarily have a large current carrying capacity; that is to say, each power rail or trolley, if continuous throughout its length, is adapted to serve admirably as a line conductor for the power transmitting system. It is practically important, however, to have the third rail or trolley made in sections which can be cut out when desired. In the present case the third rail or trolley is made sectional but the sections are normally joined together to constitute a line conductor for the power current transmission. In conjunction with this sectional third rail or trolley, there is provided the various apparatus for carrying out the train stop functions already alluded to.

In the particular illustration of the present case, the trackway is divided into blocks denominated A, B, C, D, etc., for which purpose one of the track rails 1' has insulated joints 1^x (and also 1^y) therein at the divisions between the separate blocks. The other track rail 1'' may be permanently continuous to constitute a ground return conductor for the power current transmission. It is to be noted that this arrangement of the track rails is adapted to the ordinary signal systems in use, and any ordinary signal system may be installed. All the features of the present invention are entirely independent of the signaling system proper, and operate regardless of whatever happens to the regular signaling system. Semaphores B', C' and D', are illustrated in the drawing to designate the block entrances and of course operate in the standard and well known manner. The present invention as illustrated is particularly adapted to a trackway on which trains move only in one direction; the system may be readily extended to operate with trains in both directions on a single trackway if desired. The third rail 2 is also divided into sections 14 corresponding in length to the blocks, but the joints 15 are lapped back somewhat from the block entrances. All of the third rail sections are normally interconnected along the same trackway and may be between different trackways so that they form in effect a single system of power distribu-

tion. The connection between the adjacent rail sections 14 of the same trackway, is established by branch wires 3 and switches 4.

The various switches 4 are capable of being opened so as to cut out any third rail section. The means which I have adapted for operating the switches 4 is independent of the semaphore signal system and is furthermore designed to operate with normally closed circuits throughout so as to produce a train stop actuation in case of any defect whatever.

10 denotes latches which restrain the switches 4 in their circuit closing relations 15 against the tension of springs or equivalent means 8, which are adapted to open the switches 4 when the latter are released by the latches. The latches 10 are displaced to release the switches by magnets 20 which may be arranged in any desired way. I have illustrated each latch actuated by a differentially wound magnet 11 having at least two independent windings in the present case, there being two such windings 25 through which currents flow in opposite directions so as to neutralize one another and produce an absence of resultant magnetization under normal conditions. Each differential winding of each magnet 11 is in a 30 circuit which includes the other differential winding of the next block section in advance. That is to say, the upper differential winding of the magnet 11 at section B is in a circuit which derives its current from 35 any suitable current source, through the wire 1', the circuit being continued through the wire 1² to the lower sectional winding of the next magnet 11 in advance, finally going to ground. This arrangement is 40 repeated throughout the system. Under these circumstances the two sectional windings of any particular magnet 11 are in entirely separate circuits, receiving current from separate supply points and grounded at 45 different points. Any defect in either circuit will therefore result in the unbalancing of such neutralization of two magnets 11, and the resultant magnetization will lift the corresponding latches 10 and release the corresponding switches 4. The 50 foregoing tripping means is specifically applicable to groups of two switches and constitutes one feature of my invention. The switches may be defined as being arranged in groups of two, since the circuit beginning with the wire 16 and going through the sections of wire 1, 1', 1², and 1³ to the conductor 1'' passes through two magnets 11. It is obvious, however, that the invention 55 is not limited in its combination aspects to any particular tripping means. I desire to include any style of switch tripping means for the general function of tripping groups comprising a plurality of 60 switches as a basis of the combination claims 65

on this invention, and which include other features later described. The current for the differential or tripping magnet circuits may be obtained from any suitable source; but I prefer to use therefor a special wire 70 16 extending from the train dispatcher's office and controlled by a switch 17. The latter is my preferred plan since in case of a wreck, or other extraordinary conditions, the switch 17 may be opened and a wrecking train allowed to creep up behind the stalled or wrecked train without regard to the ordinary block regulations, etc. As will later appear, I also provide means for restoring any switches 4 which have been 80 opened, to their closed positions.

The unbalancing of the magnets 11, and the tripping of the switches 4 occur for proper train stop purposes as well as defects in the circuits as above described. The 85 means by which this latter function is carried out is as follows: Reference has been made to the fact that the track rail 1' is divided into blocks by the insulated rail joints 1^x. In accordance with the present 90 invention an additional insulated rail joint is provided at 1^y for each block. The joints 1^x and 1^y are, say, one rail length, 30 feet, apart. This small section 20 may be termed a local or block entrance rail sub-division, 95 and is normally electrified by a connection m from any suitable current source 21.

n designates a circuit deriving current from the sub-division 20 and including a magnet 22, the circuit being completed to 100 the ground rail 1''. The energization of each magnet 22 normally maintains an armature 23 against its front stop 24, located in one of the differential or tripping magnet circuits, already referred to, and 105 which is normally kept closed thereby. It is to be noted that this circuit closer 23, 24, is at the location of the rearmost of the two tripping magnets 11 included in the 110 corresponding circuit.

The foregoing description applies to any block or point, but for convenience may be considered as applied particularly to the apparatus at the entrance to block C. But this apparatus also includes a magnet 26 115 which derives its current in accordance with track conditions in the block in advance (block D). The track rail section 27 of block D, which may be termed the block rail section as distinguished from the block 120 entrance rail sub-division 20, has a wire o which extends back through the magnet 26 at the entrance of block C to ground at 28. Each block rail section 27 is normally electrified by a connection r from any suitable 125 current source, so that current flows through each circuit o and magnets 26 to maintain them constantly energized. Each magnet 26 has an armature 30 which closes over the armature 23 and maintains the same against 130

its front stop, even although the magnet 22 should be temporarily deenergized. The foregoing apparatus, duplicated or repeated of course, throughout the system, is all 5 that I need provide for carrying out the first two functions described in the preliminary part of the specification.

I will consider a number of conditions which may arise in practice and show that 10 this apparatus effects a proper working under all conditions.

It may first be assumed that no trains are present anywhere in the vicinity. In this case all the magnets 22 and 26 will be energized, as already described, and current will be flowing through the differential windings of each magnet 11 to prevent the tripping of the switches 4. The third rail sections 14 will therefore be electrified. Now assume 20 that a train T^1 has proceeded through blocks A, B, and C, and has just passed on to the block rail section 27 of block D. The result will be to ground the block rail section 27 through the wheel axles, so that the current 25 which flowed through the wire o is now terminated and the magnet 26 at the entrance to block C is deenergized permitting its armature to fall. This is the only direct result of the presence of the train on block D.

30 Nor are any indirect results set up by the foregoing circumstances because the magnet 22 at the entrance to block C remains energized and keeps its armature 23 against the front stop. The corresponding tripping magnet circuit is therefore not disturbed. Now assume that a following train T^2 , approaches behind T^1 . This train may pass onto block B without effect, but on passing onto block entrance rail sub-division 20 of 35 block C, the current of magnet 22 thereat is shunted and the armature 23 falls, opening the tripping magnet circuit and unbalancing the differentially wound magnet 11 at this point. The same circuit, being continued through the magnet 11 of the station in 40 advance, also unbalances that magnet. The result is to simultaneously trip the switches 4 on both sides of block C, so that the corresponding third rail or trolley section 14 is 45 cut out. The result is to deprive train T^2 of power as soon as it intrudes on block C. This is as it should be since the following train T^2 had no right to approach so closely behind train T^1 , and should have been 50 stopped by the usual signals set against it. The point might be raised that in a train of the type having collector shoes throughout the length of a long train, there might be a lapping over of the rearmost collector shoes 55 onto a third rail or trolley section 14 behind, but this is prevented by the fact that the third rail or trolley joints 15 are spaced back a distance sufficient to obviate this possibility. The foregoing actuations occur whatever 60 the position of the advance train T^1 .

may be because wherever this train is located, it necessarily temporarily grounds some one of the block rail sections 27, and the following train T^2 can never derive current to pass through the block behind, because immediately that it attempts to do so, its power rail section becomes cut-out. But the power rail sections are not cut-out in normal working by any position of the trains, provided the latter observe the signals and traffic regulations. 70

It is unnecessary to consider in greater detail the various contingencies which might arise in practice. All circuits are normally closed and all conditions provided for so as to insure stopping the trains either on account of their own misbehavior or defects in the system. In view of this fact, a comparatively cheap and simple signal system may be employed because the train stop is 80 independent of the signal system and serves as a check on the latter, stopping the trains and preventing accidents even although the signal system might operate to give the trains an improper clear signal. 85

Self restoring features.—I provide means by which any switches 4, which have been opened, may be reclosed again as soon as normal traffic conditions are resumed. 35 is a circuit wire from the train dispatcher's 90 office from which extend branch connections p which are adapted to cause the energization of magnets 36, which in turn control the closing of the switches 4, a switch in line 35, enabling the operator to effect such 95 closure. The magnets 36 may be controlling magnets operative in any manner for effecting a closure of the switches 4 whenever energized. I have merely illustrated in 100 diagrammatic form an armature 37 joined by bell-crank and link connections to the switches 4. The circuits of the magnets 36 are so arranged that these magnets are 105 energized as soon as it is proper for a following train to derive current and proceed 110 after it has been automatically stopped as above described. For this purpose each of the circuits o which have already been mentioned and which lead from a block rail section 27, has a magnet 40 therein acting on 115 an armature 41 which is normally drawn against its front stop 42. This armature and front stop are located in the circuit p of the magnet 36 at the corresponding station. This circuit may derive current in any suitable manner, but it is most convenient to 120 merely connect it to the armature 30 of magnet 26 (previously described) and which is electrified under normal condition on account of its engagement with the armature 23 which is directly connected to the potential wire 16 by the lead l' . Under certain 125 circumstances therefore, current flows from armature 30, through front stop 42, armature 41, magnet 36, a switch 44, and wire p 130

to the line 35, which is preferably a separate wire to the despatcher's office. The switch 44 is mechanically displaced by the opening of the switches 4 to close the corresponding circuit p in any obvious manner, such for example as illustrated in the drawing. In this way the circuits p are closed at the switches 44 whenever the main switches 4 open, and current passes or not in accordance with the conditions of the armatures 41, 30. I will now analyze the different traffic conditions and show that the movements of the armatures 41 and 30, produce an energization of the magnets 36 only when 15 normal running or traffic conditions are restored.

Normally, of course, the switches 4 are retained closed by their latches and it is only when they are tripped to open that an opportunity is presented for an actuation of the restoring magnets 36. This latter condition is only normally produced by the improper separation of two trains as already described. For example, the concurrent 25 presence of two trains in blocks C and D has the effect of opening the switches 4 at both ends of block C, as already described. Assume now that train T' moves away leaving the train in block C temporarily stalled 30 without power current to proceed. As soon as the train T' passes out of block D' current is permitted to pass through the wire o from the rail 27 of this block and energize the magnet 26 at the entrance to block C. 35 The energization of this magnet attracts the armature 30 at the entrance to block C, but the armature 41 at this particular station is not attracted at this time so that the circuit p at this point is not completed. However, after the advance train T' has proceeded 40 through another block, the magnet 26 at the entrance to block D will be energized. It is evident that the magnet 40 at this station is already energized, so that the circuit p at 45 this point or station is completed. The switch 4 at the entrance to block D accordingly is closed and the power rail section 14 of block C is electrified at one end. This is sufficient to get the stalled train out of the 50 section after which the other main switch 4 closes; thus restoring the system completely to normal. It is evident that the foregoing 55 actuations of the restoring mechanism do not effect in any way the regular normal action of the armatures 23 and 30, or the tripping magnet circuit or circuit o .

In case of a wreck or other extraordinary conditions, the switch 17 is opened so as to prevent the repeated tripping of the switches 60 4, when it is intended to have a wrecking train, for example, creep up immediately behind the stalled or wrecked train.

Power feed or supply stations.—In Fig. 2 I have illustrated a slightly modified construction of the parts adapted to be pro-

vided at the power supply or distribution points of the railway. In this case it is obviously important to have a power current transmission in both directions, and the power transmission in one direction from the point of supply should not be interfered with on account of the cutting out of a third rail section on the other side of such point of supply. For example, referring to Fig. 2, 70 50' and 50'' may denote points at which power feeders supply the system. If both these points of supply were controlled by a single switch 4, it is evident that power would be cut off in both directions from the point of supply whenever said switch 4 75 opened, for example, to cut out a power conductor section on one side only, say behind the point of supply. This difficulty is overcome by providing two switches 4 and separate magnets 11 controlling the same arranged in slightly modified circuits as shown. The most prominent feature of these circuits is that the connection l' from the wire 16, 80 divides into two branches passing through the upper sections of the magnets 11. From these magnets the two branches extend forwardly and rearwardly through conductors denoted l and l^2 and have the same functions and effects as the corresponding partial circuits shown in Fig. 1. The other sections of 85 the differentially wound magnets 11 are in a simple local circuit from the potential wire 16 to the ground rail.

While I have referred in the foregoing description and in the claims to power rail or trolley sections normally joined together in an unbroken series, it is of course to be understood that in a complete railway system of the ordinary character with various power stations and power distribution points, occasional interruptions are necessary, but the words of the claims apply of course to any one of the division or units in this case, which are each virtually a complete railway in all practical purposes.

What I claim, is:

1. In an electric railway system, a sectional power conductor, switches for joining the sections of said conductor in an unbroken series, said switches having a bias for open position, holding means for retaining said switches in closed position, a plurality of normally energized circuits each including at least two electro-magnetic appliances, each of said electro-magnetic appliances controlling one of said holding devices, and means controlled by the presence of two trains spaced apart less than a determined distance for deenergizing one of said normally energized circuits.

2. In an electric railway system, a sectional power conductor, switches for joining the sections of said conductor in unbroken series, said switches having a bias to open position, holding means for retaining

each of said switches closed, electromagnetic devices for controlling said holding means, each of said devices comprising several differentially-wound windings, a plurality of 5 normally energized circuits each including windings, one in each of at least two different ones of said devices, train controlled means for deenergizing one of said circuits and thereby opening the switches controlled 10 thereby, and means for restoring said switches to closed position.

3. In an electric railway system, a sectional power conductor, switches for joining the sections of said conductor together in an 15 unbroken series, said switches having a bias for open position, holding devices for retaining each of said switches in closed position, means comprising a circuit including electro-magnetic appliances through which 20 current normally flows, for controlling a limited number of said holding devices, two separate normally energized auxiliary circuits each having an electro-magnetic device therein, and means controlled by said electro-magnetic devices for interrupting the 25 current flow in said first mentioned circuit, said means interrupting said current flow when both of said electro-magnetic devices are deenergized.

30 4. In an electric railway system, a sectional power conductor, switches having a bias to open position for joining the sections of said conductor together in an unbroken series, holding means for maintaining said 35 switches closed, means comprising normally energized circuits each including an electro-magnetic device for disengaging one of said holding means, said last mentioned means being inoperative as long as current flows 40 through said circuits, separate auxiliary circuits each having a magnet therein through which current normally flows, said last-named circuits being deenergized by the presence of two trains at determined points 45 along the trackway, and armatures for said magnets, one of which armatures closes one of said first-named circuits and the other of which armatures when attracted holds the first armature in its circuit closing relation.

50 5. In an electric railway system, a sec-

tional power conductor, switches normally joining the sections together in an unbroken series, differentially wound magnets for controlling said switches, and a plurality of circuits each including winding on each magnet of a group of said magnets through 55 which current normally flows.

6. In an electric railway system, a sectional power conductor, switches normally joining the sections together in an unbroken 60 series, differentially wound magnets for controlling said switches, circuits each including a winding on each of a group of said magnets, a common source of supply for normally energizing said circuits, and means at 65 the despatcher's station for interrupting said supply.

7. In an electric railway system, a sectional power conductor, switches normally joining the ends of the sections together in 70 an unbroken series, means actuated by two improperly spaced-apart trains for opening a plurality of said switches relatively adjacent to each other as compared to the length of the power conductor, and means comprising circuits each completed at one point by the opening of one of said switches, and electrical appliances controlled by said circuits, for restoring the switches to closed 75 circuit positions when normal traffic conditions of the trains are resumed.

8. In an electric railway system, a sectional power conductor, switches for joining the sections of said conductor together in an unbroken series, means for opening 85 said switches, controlling means for said switch opening means, said controlling means comprising differentially wound magnets, separate circuits each including a winding of a magnet and means for altering the 90 circuit conditions in said separate circuits, said last mentioned means including normally energized auxiliary circuits controlled by the movement of trains along the track.

In testimony whereof, I subscribe my signature, in the presence of two witnesses.
